BLOCK OUT SYSTEM FOR DUPLICATING

Rembert A. Marquardt and Stuart C. Morrey,
Park Ridge, Ill.No Drawing. Application June 15, 1948,
Serial No. 33,238

2 Claims. (Cl. 282—28)

1

The present invention relates to the duplicating art. It is particularly directed to the provision of a copy sheet on which copies are to be made by applying hectographic ink thereto from a master sheet, with means to cancel a portion of the copy impressed thereon so that this cancelled portion cannot be recognized. In the duplicating art, it has long been recognized that for certain purposes, it is an advantage to be able to block out certain information carried on the master sheet so that one or more copies will be free of the blocked out information. It is common practice in hectograph duplication to employ "block out" sheets which are superimposed on the master sheet when it is desired to prevent certain information on the master from being communicated to the copies. In the gelatin pad type of hectograph duplicator, the block out sheet may be applied over a portion of the gelatin pad while the abbreviated copy is being made. With the liquid process type of duplicating where the master copy is formed in reverse script on a sheet of paper and is transferred to the copy sheet by applying a solvent for the hectographic ink to the copy sheet, the block out sheet is placed over that portion of the reverse master that is to be excluded from the copy. These methods of excluding certain matter from certain copy sheets do not lend themselves to efficient operation where a large number of copies have to be made, since they require the operator of the machine to apply and remove the block out sheets at the proper time. Also there is always the possibility that a block out will not be applied when it should be and the copy sheet intended to receive only part of the information from the master will receive all of it.

It is the purpose of the present invention to provide a copy sheet for liquid process type of hectograph duplication that will completely mask the information transferred to certain portions thereof by taking and spreading the hectographic ink deposited on the copy sheet in such a fashion that the outlines of the deposited area can no longer be recognized. To this end the invention contemplates the provision of a copy sheet set for use in liquid process duplicating machines which set will contain one or more sheets, certain areas of which are so treated as to prevent a legible or decipherable impression from the master with which the sheets in the set are used. The invention embodies the impregnation of a portion of the copy sheet with a substance, porous to the usual solvents and including a water and alcohol

2

soluble dye of like nature to that used in an ink of the hectograph type, which substance can be applied to the copy sheet during the printing operation in which the heading and other permanent information is applied to the copy sheets.

It is a further purpose of the invention to provide a novel process of preparing a copy sheet with block out areas capable of absorbing hectographic ink in a duplicating process in such fashion as to make the specific areas contacted by the ink areas on the master unrecognizable on the copy sheet.

It is a further purpose of the invention to provide a novel copy sheet treating substance which may be applied to the copy sheet by ordinary printing processes and which, when so applied, impregnates certain areas of the copy sheet with a coloring matter soluble in the usual solvents for the hectographic ink used on the master

10 sheets, without destroying the absorbent qualities of the impregnated areas of the copy sheet for the hectographic ink from the master so that the ink, when absorbed from the master, is lost by intermingling with the impregnated coloring 15 matter in the copy sheet.

20 Our invention is not applicable to the taking of copies from a moistened gelatin pad which has received the master copy in reverse from an original in hectograph ink for the reason that the moist gelatin pad will pick up the coloring matter from the blocked out area of the copy sheet and transfer it to another sheet.

25 The form lines on the copy sheet are printed with any suitable printing ink. The areas which are to mask the hectographic ink legend impressed thereon in the usual liquid process duplication, are printed during the printing operation with a substance containing a water-alcohol soluble dye of a similar color or a dominant to that of the water soluble dye used in the hectographic ink that is employed in the duplicating process. There are a great number of these dyes used. For example, in the Hoskins Patent No. 2,088,417, for a process of improving light fastness and moisture resistance of hectograph copies, such dyes as methyl violet, crystal violet, fuchsines, magentas, anthroquinones. Chrysoidine, aniline dyes such as aniline blue, Victoria blue and orange, Nile blue, and azo dyes such as Congo red and Bismarck brown, are listed as examples of water and alcohol soluble dyes that may be used in making copies by the hectograph process.

30 The substance for impregnating the areas that 35 are to be "blocked out" must be carefully pre-

pared in order to work in a printing press. As illustrative of the method of preparing the substance and the ingredients used therein, the following example is set forth.

First boil together for about one hour a mixture of 1 part by weight British gum and 3 parts by weight glycerin until the mixture reaches a consistency slightly heavier than pouring. Prepare another mixture of 50 per cent by weight diethylene glycol and 50 per cent by weight white 10 dextrine by boiling them together for about twenty minutes until the mixture reaches a solution slightly heavier than pouring.

Take 10 parts by weight of the first mixture, 14 parts by weight of the second mixture, 23 parts by weight diethylene glycol, 45 parts calcium carbonate (White Carb Dry White), and 10 parts by weight of a water and alcohol soluble dye such as methyl violet diluted to the standard known in the trade as 2 B concentrate 125%. Mix these ingredients thoroughly by running them through an ink mill several times to produce a concentrated ink solution.

The concentrated ink solution is prepared for press use as follows: First prepare by boiling to a consistency slightly heavier than pouring, 1 part gum arabic and 9 parts glycerin, both by weight. Mix 3 parts of this substance with 5 parts diethylene glycol, 16 parts of the concentrated ink and about 1 part of commercial Le 30 Page's strength glue, all parts by weight.

The resulting block out ink may be used on such printing presses as Miller Major flatbed presses and Miehle vertical presses. The presses must be equipped with rubber rollers and the type may be either rubber or metal. No special technique is required in the printing. The ink may be applied solid on the block out areas, or, a variegated design having small areas devoid of ink may be used. In the printing it is necessary, of course, to use suitable copy sheets such as are commonly used for copy sheets in hectograph duplication. The sheets treated as described in the Hoskins patent, heretofore referred to, and others may be used. We find that the areas to which the block out ink is applied are impregnated with the ink substance to a depth generally exceeding twenty per cent of the thickness of the ordinary copy sheet paper. The ability of the impregnated area to absorb solvents for hectographic ink is, however, as great as that of the rest of the copy sheet.

When the copies are made in accordance with the common practice from a master sheet, those copies containing the inked block out areas will receive the same impression as other copy sheets not having the inked areas. However, on the copy sheets having the inked block out areas, that part of the information contained on the master sheet which is impressed on the inked block out areas loses its identity immediately on contact with the inked areas. The application of the ink described above provides a body of color which is absorbent with respect to the solvent used in the duplicating process, so that the dye transferred from the master sheet with the solvent spreads into and becomes an indistinguishable part of the color body. It cannot be identified, even under a high power microscope, since the solvent appears to effect sufficient softening of the impregnated color to cause the transferred dye to become intermingled therewith. Where the variegated design with small non-colored areas is used on the block out portions, it is possible to detect the dye deposit on

the white portions of the paper, but these white portions are of such small dimensions that they give no indication by reason of the deposits thereon of the outline of the figure character or design transferred.

5 The masking of the coloring matter transferred from the master copy is not dependent upon the dye in the block out substance being of the same color as that in the hectographic ink transferred from the master copy. Preferably we employ the darker colors such as methyl violet, crystal violet, aniline blue and Nile blue in the block out substance because of the more solid appearance. However, examples that we have run show that a single color in the block out effectively blocks out several others. A block out area wherein the water-alcohol soluble dye used was methyl violet masked out red, green, blue and purple transfers from masters having the reverse script legend formed by using hectograph carbons made by Ditto Incorporated. Likewise where a black water-alcohol soluble dye is used in the block out substance applied to the copy sheet, the legends in greens, blue, violets and browns are no longer readable when transferred to the block out area.

20 In the actual making of copies utilizing our invention, it is customary to print on business forms, such as invoices, with ordinary oil base printing ink the proper general heading and line arrangement. Several copies of each invoice or order may be needed. Not all of these copies require the same information. For example, one copy will require all of the information itemized such as size, base price, discount to distributor, discount to jobber, salesman commission and total price for each item. Other copies such as those used for shop orders, check lists and the like, should not have the discount and base price columns filled in. The printer who has the order for the forms, will print each copy, using block out substance on the copies that are not required to have certain information. Then the copies for the several uses are assembled together in a set which includes one or more of the copy sheets carrying the block out substance. The various sheets are marked to indicate who gets them, as master copy, customer's copy, etc.

25 When the master copy is made, usually on a typewriter, a hectograph carbon on the back of it provides a duplicating master so that liquid process duplication is used to make the other copies of a set. There is no danger of an error being made by the operator to place undesired information on one of the block out copies.

30 In applying the impregnating block out substance, we cause it to penetrate the paper stock to a depth of about twenty per cent of the thickness of the paper or more. The depth of penetration depends upon the porosity of the copy sheet used. When the ink dissolved from the master contacts the block out area, the transferred ink blends with the coloring matter in the impregnating substance, since both are soluble in the solvent used to moisten the copy sheets, and they are pressed deeply into the copy paper. The penetration is shown by microscopic examination, to be increased over the entire block out area by the moistening of the copy sheet and passing it between the master sheet and the pressure roller of a duplicating machine.

35 The block out substance must be sufficiently fluid to penetrate the copy paper to a substantial distance when it is applied. It is also porous when dried, so the solvent enters it readily.

Otherwise the surface accumulation of this substance will be transferred to the master sheet and reprint onto the succeeding copy sheets. Also, the substance has apparently a greater affinity for the copying ink than the copy paper has. It quickly removes most of the copy ink from the master if it is merely surface coated onto the copy paper.

It is believed that the nature and advantages of our invention will be apparent from the foregoing description.

Having thus described our invention, we claim:

1. A method of blocking out parts of a copy sheet in the taking of copies from a reverse master copy by hectograph duplication which comprises impregnating certain of the areas of a copy sheet to be moistened and contacted with the master copy with an ink substance, the color base of which is a water and alcohol soluble dye, the depth and quantity of the ink substance impregnation being substantially greater than that of the hectographic ink transferred by the act of contacting the moistened copy sheet with the reverse legend on the master sheet, applying solvent to the copy sheet and pressing it against the reverse master, thereby transferring legible copy to clear parts of the copy sheet and masking the copy transferred to the impregnated areas of the copy sheet by diluting and blending the ink dissolved from the master sheet with the moistened impregnating substance.

2. In the art of duplication by pressing a copy sheet against a master sheet having the copy thereon formed of a water and alcohol soluble hectographic ink, and moistening the contacting surface of one of said sheets with a solvent for the ink, the method of rendering part of the copy transferred undecipherable, which comprises impregnating the area of the copy sheet receiving said part of the copy with an ink substance previous to water and alcohol, the coloring matter of which comprises a water and alcohol soluble dye moistening the contacting surface of one of the sheets with a solvent for the hectographic ink, pressing the copy sheet against the part of the master sheet having the copy thereon formed of hectographic ink, and thereby blending the transferred ink of the copy with the dye in the ink substance.
